(57) CLAIM

The ornamental design for a garment bottom, as shown and described.

DESCRIPTION

FIG. 1 is a rear perspective view of a garment bottom showing our new design;

FIG. 2 is front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The evenly dashed broken lines in the drawings depict stitching that form no part of the claim. The broken dot-dashed lines define the bounds of the claim and form no part thereof.

1 Claim, 4 Drawing Sheets
